ATTACHMENTS TO CRUTCHES

Philip Faircleugh Douglas, Carman, Manitoba,
CanadaApplication September 20, 1941, Serial No. 411,752
In Canada September 19, 1940

3 Claims. (Cl. 135—50)

My invention relates to attachments to crutches, a principal object of the invention being to provide arrangements of the character hereinabove described, by the use of which considerably greater comfort may be derived by the user, together with a substantial reduction in the shock caused each time the crutches strike the ground.

A further object of my invention is to provide in crutches, arrangements by the use of which greater speed of locomotion becomes possible, or in other words, longer strides with the use of crutches fitted with my hereinafter described arrangement.

A further object of my invention is to provide a ferrule attachment, which is economical to manufacture, easy to attach and which will not become out of order as and for the above purpose.

With the above more important objects in view and such other minor objects as may appear as the specification proceeds, my invention consists essentially in the arrangement and construction of parts all as hereinafter more particularly described, reference being had to the accompanying drawing, in which:

Figure 1 is a sectional side elevation of my invention, showing the same in situ on the crutch.

Figure 2 is a modified form of my invention using a different type of a plunger.

In the drawing like characters of reference indicate corresponding parts in the different figures.

It is well known that considerable discomfort is experienced by cripples who are obliged to resort to the use of the crutches, through the unyielding construction thereof and that the speed, freedom of movement and safety of such persons are greatly hampered by expectations of a shock which is transmitted to their body every time a step with the crutches is taken.

My arrangements herewithin described and illustrated in the accompanying drawing are therefore designed to overcome the above objections, and referring first to my ferrule attachment 1 shown in Figure 1, this will clearly be seen as attached to the crutch 2 below the junction of the forked end 3. In this context I would remark that generally speaking, it will be found necessary to cut off a portion of this end of the crutch below the junction of the forks.

My attachment 1 comprises a hollow open-ended and tapered sheath 4 secured to the forked shank by means of the bolts 5. The elongated aperture 6 at the lower end of the sheath is internally screw-threaded as at 7 to receive the upper, externally screw-threaded shank of a plunger 8. 55

The lower end of the plunger is of an increased diameter as at 9, designed for a free sliding fit within a ferrule 10, and is provided with an axial, cylindrical cavity 11. A pair of compression springs 12 and 13 of different resiliencies are positioned in this cavity and extend between the plunger 9 and the lower wall 14 of the ferrule.

The two different diameters of the plunger 8 provide an annular shoulder 15 designed to engage the lower annular perimeter of a boss 16 when the springs 12 and 13 are in relaxed position. The boss is provided at the upper end thereof with an outwardly projecting annular flange 17, below which it is externally screw-threaded, as at 18, to engage the internally screw-threaded upper end 19 of the ferrule 10.

Referring now to the accompanying Figure 2, a modified arrangement of my invention will be seen, in which the plunger 8 is provided with a cylindrical portion 20 of an enlarged diameter, the piston surface 21 of which bears against the inside wall of the ferrule 10.

The lower end 22 of the plunger is of a reduced diameter and extends into a coil spring 23, which in turn is positioned within the cavity 11 of the ferrule 10. In all other respects this embodiment is similar to that shown in Figure 1, including the provision of a conventional rubber ferrule 24 as will clearly be apparent from the drawing.

From the foregoing will be seen that when the weight of the user is exerting a downward pressure upon the crutch, the springs 12 and 13 will become compressed, so that in the action of walking with crutches fitted with my ferrule attachment, the tendency of the springs to relax will greatly assist the user in his motion.

I also wish to point out that any possibility of wobble in my ferrule attachment is eliminated by the piston surface 21 which being of substantial length and in engagement with the inner wall of the ferrule 10 prevents any side play of the plunger 8.

Since various modifications can be made in my invention as hereinabove described and as illustrated in the accompanying drawing, and many apparently widely different embodiments of same made within the scope of the claims without departing from such spirit and scope, it is intended that all matter contained in the accompanying specification and drawing shall be interpreted as illustrative only and not in a limiting sense and I desire only such limitations placed thereon as are specifically expressed in the accompanying claims.

What I claim as my invention is:

1. Attachments to crutches comprising in combination, a hollow tapered sheath designed to encase the lower forked ends of crutches, the lower end of said sheath being apertured and internally screw-threaded, a plunger externally screw-threaded at the upper end thereof to engage the internally screw-threaded portion of said sheath, a ferrule, a coil spring therewithin, the upper end of said ferrule being internally screw-threaded, an externally screw-threaded boss engageable with the internally screw-threaded upper end of said ferrule, an external annular flange adjacent the upper end of said boss and engageable with the upper perimeter of said ferrule, said plunger extending through said boss into said ferrule, the lower end of said plunger having an axial, cylindrical cavity formed therein to receive the upper end of said spring.

2. The device as defined in claim 1 in which the lower end of said plunger is in frictional engagement with the inside wall of said ferrule.

3. Attachments to crutches comprising in combination, a hollow, tapered sheath designed to encase the lower forked ends of crutches, the lower end of said sheath being apertured and internally screw-threaded, a plunger externally screw-threaded at the upper end thereof to engage said internally screw-threaded portion of said sheath, a ferrule, a coil spring therewithin, the upper end of said ferrule being internally screw-threaded, an externally screw-threaded boss engageable with the internally screw-threaded upper end of said ferrule, an external annular flange adjacent the upper end of said boss and engageable with the upper perimeter of said ferrule, said plunger extending into said ferrule through said boss, a cylindrical block formed intermediately the length of said plunger and in frictional engagement with the inside wall of said ferrule, the lower end of said plunger extending into the upper end of said spring.

PHILIP F. DOUGLAS.
